UNITED STATES PATENT OFFICE.

THORNTON W. LOSEY, OF SILVER GROVE, KENTUCKY.

COMBINATION TOOL.

Application filed May 13, 1927. Serial No. 191,171.

Railroad mechanics engaged in making adjustments or repairs beneath rolling stock, particularly when working on the brake mechanism, require a variety of tools to meet different conditions and location of parts in order to expedite the work and minimize the hazard to obviate maiming of the hand by the severing of a digit thereof. It is not always convenient or practical to have the necessary tools at hand and in consequence loss of time is experienced and occasioned by the mechanic in getting from beneath the car to obtain a needed tool and returning to the work. This is also a prolific source of annoyance and discomfort to the workman which is overcome by the present invention.

Therefore, it is the primary intention of this invention to provide in a single organization instrumentalities for effecting results as the exigencies of the work may demand, said instrumentalities being disposed for convenience of use without resulting in the provision of a cumbersome and unwieldy tool.

The invention provides a tool having the general characteristics of a hammer, since it embodies a head and a handle, and these essential parts are modified to provide the means necessary to meet the requirements encountered in the adjustment and repairing of car-brake mechanism.

While the drawings illustrate a preferred embodiment of the invention, it is to be understood that in adapting the means to meet specific needs and requirements, the design may be varied and such other changes in the minor details of construction may be resorted to within the scope of the invention as claimed without departing from the spirit thereof.

For a full understanding of the invention and the merits thereof, reference is to be had to the following description and the drawings hereto attached, in which,

Fig. 1 is a side view of a railroad mechanic's combination tool embodying the invention;

Fig. 2 is a transverse sectional view of the head on the line 2—2 of Fig. 1, showing a portion of the handle fitted thereto, and the dotted lines indicating the application of the tool to a cotter-pin;

Fig. 3 is a reverse side view of the head portion of the tool.

Fig. 4 is a top plan view of the tool; and Fig. 5 is a view similar to Fig. 4 of a modification.

Corresponding and like parts are referred to in the following description and 60 designated in the several views of the drawing by like reference characters.

The tool comprises essentially a head 10 and a handle 11, the latter being usually of wood and fitted to the head 10 in which 65 is formed an opening into which an end of the handle 11 is fitted.

The head 10 has the general outline of a peen hammer, one end of the head constituting the poll 12, and the opposite end 70 of the peen 13 which in the present instance is of conical form and of a size for backing out the key bolt. The base of the peen 13 which constitutes in effect a drift, corresponds approximately to the diameter of 75 the poll 12, thereby admitting of the poll 12 being utilized temporarily as a key in an emergency. The outer end 14 of the handle 11 is of tapering form to correspond with the outline of the part 13, thereby admitting of its use as a device for alining parts to receive the key bolt, thereby eliminating the necessity or occasion for inserting the finger as is now sometimes done, with frequent disastrous results. If desired, the end of the tapered part 14 of the handle may be metal tipped, as indicated at 80 15, so as to reinforce the same and resist wear.

An opening 16 is formed in a side of the 90 head 10 and is designed to receive a leg or element of a cotter-pin, as illustrated most clearly in Fig. 2 of the drawing. The outer wall 17 of the opening 16 is relatively thin and its forward end is beveled to admit of 95 its ready entry between the legs or elements of a cotter-pin. The wall 17 functions as a spreader when it is required to separate the side elements of a cotter-pin to prevent its casual displacement after being 100 placed in position. It is also observed that when it is required to remove the cotter-pin the spread ends may be straightened or brought together by introducing one at a time into the opening 16 and manipulating 105 the tool to bring the elements or spread portions of the cotter into close relation, so that the pin may be removed.

A recess 18 is formed in the opposite side of the head 10 and is of angular outline, 110

being preferably square to conform to the outer end of a pipe back out. It will thus be understood that the recess 18 constitutes in effect a wrench socket. A constricted opening 19 leads outwardly from the recess 18 and provides a throat or clearance to receive the body of a cotter-pin, the head of which is received in the recess 18 when the tool is used in the capacity of a cotter-pin 10 remover or extractor.

In some instances it may be advantageous to differently position the opening 16, and in Fig. 5 is shown such opening disposed in the angle formed between the base of 15 the peen 13 and the bulged side portion of the head. The opening thus formed is indicated by the numeral 16^a and is defined by an angular wall 17^a. This arrangement admits of operation upon a cotter-pin which 20 is located close to the bar and which otherwise would be difficult to reach, but which is readily accessible by the construction illustrated in the modification. In either 25 arrangement of the opening its inner wall is curved to conform to the outer curved surface of a cotter-pin and the outer thin wall is flat to pass readily between the legs of a cotter-pin and conform to the flat sides thereof. The opening extends entirely through 30 the outer and inner faces of the head, as shown most clearly in Figure 2 of the drawings, and in consequence the tool may be applied so that a leg of the cotter-pin may enter either end of the opening as found 35 most convenient. This results in the formation of an opening having its inner wall rearwardly deflected to approximate the curvature of the outer surface of a cotter- pin.

40 A side of the handle 11 is provided with scale graduations for convenience of meas-

urement in determining the minimum and maximum brake piston travel.

It will be readily understood that the invention results in the provision of a tool 45 embodying the essentials necessary for adjusting and repairing the brake mechanism of railway cars, and enables the work to be expedited and obviates the necessity of the mechanic getting from under the car after reaching a position for work. It is observed that the tool embodies a hammer, a drift, a cotter-pin spreader, a cotter-pin straightener and extractor, a wrench, a drift for the 50 removal of key bolts, a tool for replacing the key bolts when required, and a rule for making measurements in determining brake travel. It is further observed that the tool is compact and of a formation to admit of 55 convenient and ready manipulation.

It is also noted that it combines a plurality of tools in one thereby decreasing labor and materially increasing safety.

Having thus described the invention, I 60 claim:

1. A tool comprising an elongated head having a handle projecting therefrom intermediate its ends, and having a side portion bulged and formed at an end of the bulge with an opening which is closed at its outer 65 adjacent sides by thin walls which are angularly disposed.

2. A tool comprising a handle and a head at one end of the handle projecting beyond the sides thereof, and having an opening 70 in a side portion of the head extending through the inner and outer faces thereof, the inner wall of the opening being rearwardly deflected and the outer wall thin and flat.

In testimony whereof I affix my signature.
THORNTON W. LOSEY. [L.S.]
